UNITED STATES PATENT OFFICE.

JOHN H. SWARTZ AND DE WITT C. TAYLOR, OF BROOKLYN, ASSIGNORS TO
THE BELL METER COMPANY, (LIMITED,) OF NEW YORK, N. Y.

WATER-METER.

SPECIFICATION forming part of Letters Patent No. 233,446, dated October 19, 1880.

Application filed January 9, 1880.

To all whom it may concern:

Be it known that we, JOHN H. SWARTZ and DE WITT C. TAYLOR, of the city of Brooklyn, county of Kings, and State of New York, have 5 invented a new and Improved Water-Meter, of which the following is a specification.

Our invention relates to improvements on the rotary water-meter for which Letters Patent No. 197,949 were granted to John H. 10 Swartz, December 11, 1877.

The object of our invention is to improve the construction and operation of the inlet-pipe and the direction-plate; also, to provide an exit to the meter for the leakage in the 15 inlet-pipe when the valve is closed, so that the leakage can be measured, without, however, permitting the flow of auxiliary streams when the valve is open.

A further object of our invention is to adjust 20 the leverage of the registering mechanism to the pressure of the water.

Other objects of our invention will be referred to in the description of the several parts of the invention and their operation.

25 In the accompanying drawings, Figure 1 is a horizontal section of our improved water-meter, taken on line *c c* of Fig. 2. Fig. 2 is a vertical longitudinal section, taken on line *k k* of Fig. 1. Fig. 3 is a perspective view of the 30 inlet-pipe and valve, and Fig. 4 is an end elevation of the entrance-port.

Referring to the drawings, *A* represents the lower part of the meter-box; *B*, the upper part of the same. *C* is the registering mechanism. *D* is the entrance-port. *D'* is the exit-port, and *a* is the glass face through which the register is read. *E* represents the inlet-pipe, which is provided with a circular flange, *b*. The inlet-pipe is inserted in the port 40 *D*, so that its triangular open inner end, with its valve *d*, projects just within the valve-box *A*, while the collar or flange *b* bears against the end of the port *D* and holds the inlet-pipe immovable within the said port, pins *s* projecting through holes in the flange *b* to prevent the pipe *E* from turning. A cap, *F*, is 45 screwed over the end of the port and against the flange *b*, to fasten the inlet-pipe in the front, and the outer end of this cap is provided

with a screw-threaded socket for the connection of the supply-pipe. 50

One side, *e*, of the entrance-port is straight, so as to serve as a guide for inserting the inlet-pipe, the straight side being on the side of the hinged end of the valve. 55

A rod, *G*, extends from the valve *d*, through the cross-bar at the outer end of the inlet-pipe, and around this rod *G* the spiral spring *e'* is wrapped, which holds the valve shut. By pushing on the end of the rod the valve can 60 be opened without removing the inlet-pipe to clean out, inspect, or repair the meter. The upper end of the valve is provided with a notch, *f*. Through this notch, when the water is shut off, any leakage from the supply-pipe 65 into the inlet-pipe escapes into the meter, and is measured in the same way as the water that passes through when the valve is open. By having the notch *f* in the valve it does not affect 70 the passage of the water from the inlet-pipe, as it would were the opening for the passage of the leakage in the inlet-pipe itself, in which case a definite stream would pass from the inlet-pipe in addition to that passing through the valve-opening, whereas it is necessary 75 to the proper working of the meter that all the water should pass through the valve-opening, so that the size of the exit can be adapted (by the opening and closing of the valve under the influence of the pressure of 80 the water and the restraint of the spring) to the pressure of the water.

The notch or opening *f*, in addition to providing an exit for the leakage into the meter, also supplies an opening for the back flow of 85 the water from the distributing-pipes and the meter to the water-pipes, when the water-supply is shut off, thereby permitting the water to escape and preventing freezing in the pipes. 90

g is a plate pivoted to the outside of the valve, which is adapted to be turned so as to partially or entirely close the notch *f*, and thereby regulate the exit of the leakage from the inlet-pipe. 95

H is the direction-plate. It has its fixed end attached to the inlet-pipe, instead of the meter-body, as heretofore, while its free end

projects over and beyond the swinging end of the valve *d*. By attaching the direction-plate to the inlet-pipe it is made removable therewith, and brought closer to the valve-opening 5 when the water is passing through, whereby the water ejected from the inlet-pipe in a small stream comes more quickly in contact with the direction-plate, and is deflected down upon the wings of the registering apparatus.

10 *h* is the set-screw or other regulator for adjusting the angle of the direction-plate. Its outer end is confined within a box, *i*, provided with a screw-cap, *j*.

15 *h'* is the set-screw for regulating the opening of the valve *d*. The outer end of the set-screw *h'* is confined in a similar box, *i'*, provided with a similar cap, *j'*. The object of the boxes and caps is to prevent leakage from the valve by the passage of the water around the 20 set-screws. As the boxes will, in case of leakage, fill with water in a short time, a water-packing will be provided which will prevent a further waste of water from the same source.

25 The object of the regulator *h'* is to limit the possible opening of the valve *d*, and thereby, also, the direction and speed of the issuing stream.

30 The wings *I* are held on the arms *l l* of the shaft of the registering apparatus by eyes *m* and set-screws *n*. This permits the said wings to be adjusted to and from the central shaft, and thereby increase or decrease their leverage, so that the leverage they exert on the 35 registering apparatus can be adjusted to the pressure of the water passing through the meter.

35 *K* is a thimble-shaped screen or sieve, which is placed over the outer end of the inlet-pipe to prevent the entrance of fish and solid materials of any kind into the inlet-pipe and meter. The spring-rod passes freely through this sieve, 40 as shown.

The stop *h'* in the meter-box serves also as a means of giving direction to the large stream, and thereby to regulate the effect of the stream 45 upon the registering mechanism of the meter.

We claim—

1. The meter-box *A*, having inlet-port *D*, which is provided with a straight side, *e*, in combination with the removable inlet-pipe *E*, 50 said straight side being adapted to guide and facilitate the insertion of the said inlet-pipe, substantially as described.

2. The guide-rod *G*, in combination with the valve *d*, with the spring *e'*, which surrounds 55 said rod, and with the inlet-pipe *E*, the outer end of the rod passing loose through a guide-piece in the inlet-pipe, the inner end of said rod, and also that of the spring, being directly connected with said valve, substantially as 60 specified.

3. The pivoted plate *g*, in combination with the valve *d*, provided with the notch *f*, substantially as described.

4. In combination with the plate *H* and set-screw *h*, the box *i*, provided with the screw-cap *j*, as and for the purpose substantially as described.

5. The meter-wings *I*, adjustable on the arms *l*, in combination with the registering mechanism *C* and inlet-pipe *E*, substantially as 70 described.

6. In a water-meter, the combination of the inlet-pipe *E*, direction-plate *H*, meter-box *A*, and wings *I* with the adjustable stop *h'*, and 75 with the hinged valve *d*, all arranged to operate substantially as herein shown and described.

JOHN H. SWARTZ.
DE WITT C. TAYLOR.
